DESIGN FOR A LIQUID DISPENSER

Abraham Levy and Joseph F. Punzak, Brooklyn,
N. Y.

Application May 20, 1940, Serial No. 92,481

Term of patent 3½ years

To all whom it may concern:

Be it known that we, Abraham Levy, a citizen of the United States, residing at Brooklyn, in the county of Kings and State of New York, and Joseph F. Punzak, a citizen of the United States, residing at Brooklyn, in the county of Kings and State of New York, have invented a new, original, and ornamental Design for a Liquid Dispenser, of which the following is a specification, reference being had to the accompanying drawing, forming part thereof.

We claim:

The ornamental design for a liquid dispenser, as shown.

ABRAHAM LEVY.
JOSEPH F. PUNZAK.
